(57) **CLAIM**

The ornamental design for a mini electric screwdriver pen, as shown and described.

DESCRIPTION

FIG. 1 is a front, right, top perspective view of the mini electric screwdriver pen, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is a front, right, top perspective view of its reduced scale in a detached state;

FIG. 10 is a rear, left, bottom perspective view of its reduced scale in a detached state;

FIG. 11 is an enlarged view of detail 11 in FIG. 9;

FIG. 12 is an enlarged view of detail 12 in FIG. 9; and,

FIG. 13 is an enlarged view of detail 13 in FIG. 9.

The dashed broken lines in the figures are for the purposes of illustrating portions of the mini electric screwdriver pen and form no part of the claimed design.

The dash-dot-dash broken lines are for notating enlarged views and form no part of the claimed design.
